(57) **CLAIM**

The ornamental design for a smart camera, as shown and described.

DESCRIPTION

FIG. 1 is a front view of a smart camera showing our new design, with the camera support omitted for ease of illustration;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof;

FIG. 8 is a bottom, rear and left side perspective view thereof;

FIG. 9 is a front view of the camera support, shown with the camera omitted for ease of illustration;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a top, front and right side perspective view thereof;

FIG. 16 is a bottom, rear and left side perspective view thereof;

FIG. 17 is a front view of the camera support, shown with the camera and the camera support attached and fully extended;

FIG. 18 is a rear view thereof;

FIG. 19 is a left side view thereof;

FIG. 20 is a right side view thereof;

FIG. 21 is a top plan view thereof;

FIG. 22 is a bottom plan view thereof;

FIG. 23 is a top, front and right side perspective view thereof;

FIG. 24 is a bottom, rear and left side perspective view thereof;

FIG. 25 is a top, front and right side perspective view thereof, shown fully retracted;

FIG. 26 is a top, front and left side perspective view thereof, shown fully extended;

FIG. 27 is a top, rear and left side perspective view thereof, shown in a first alternate position;

FIG. 28 is a top, rear and left side perspective view thereof, shown in a second alternate position; and,

FIG. 29 is a top and right side perspective view thereof, shown in a third alternate position.
